BOTTLE OR SIMILAR ARTICLE

Victor Koenigsberg, Franklin Square, N.Y., assignor to Colgate-Palmolive Company, New York, N.Y., a corporation of Delaware

Original design application Nov. 21, 1967, Ser. No. 9,489, now Patent No. 214,873, dated Aug. 12, 1969. Divided and this application Dec. 23, 1968, Ser. No. 15,383

Term of patent 14 years

Int. Cl. D9—01

U.S. Cl. D9—118

Fig. 1

Fig. 3

FIG. 1 is an elevational view of a bottle or similar article embodying my new design;

FIG. 2 is a top plan view thereof; and

FIG. 3 is a bottom plan view thereof.

The side opposite that seen in FIG. 1 is substantially the same in appearance as the side shown.

This application is a division of my earlier filed application Ser. No. D. 9,489, filed Nov. 21, 1967, now Pat. No. D. 214,873, patented Aug. 12, 1969.

I claim:

The ornamental design for a bottle or similar article, as shown and described.
